UNITED STATES PATENT OFFICE.

JOHN H. BARR, OF SYRACUSE, NEW YORK, ASSIGNOR TO REMINGTON TYPEWRITER COMPANY, OF ILION, NEW YORK, A CORPORATION OF NEW YORK.

TYPE-WRITING MACHINE.

1,016,927.

Specification of Letters Patent. Patented Feb. 13, 1912.

Application filed August 21, 1911. Serial No. 645,210.

To all whom it may concern:

Be it known that I, JOHN H. BARR, citizen of the United States, and resident of Syracuse, in the county of Onondaga and State 5 of New York, have invented certain new and useful Improvements in Type-Writing Machines, of which the following is a specification.

My invention relates more particularly to 10 the ribbon mechanism of typewriting machines and has for its main object the provision of improved means for controlling the vibratory movements of the ribbon under the operation of the printing keys in 15 order to vary the widthwise portion of the ribbon presented to the types.

A further object of my invention is to 20 provide ribbon controlling means of the character specified which is particularly applicable to typewriting machines in which a shifting platen is employed, the ribbon controlling means operating in either position to which the platen may be shifted.

To the above and other ends my invention 25 consists in the features of construction, combinations of devices and arrangements of parts hereinafter described and particularly pointed out in the claims.

My invention is shown herein as applied 30 to a machine essentially resembling the No. 10 Remington typewriting machine but the nature of the invention is such that it may be readily adapted to other styles of writing machines.

In the accompanying drawings, Figure 1 35 is a rear elevation partly in section of a Remington No. 10 typewriting machine embodying my invention, parts of the machine being omitted and parts broken away. Fig. 40 2 is a vertical front-to-rear central sectional view of said machine. Fig. 3 is a fragmentary side elevation with parts in section illustrating some of the parts shown in Fig. 2 as they appear when the platen is shifted. 45 Figs. 4 and 5 are fragmentary operating views as seen from the left-hand side of the machine, Fig. 4 showing the parts in operative position when set for presenting the upper field of the ribbon to the types; and Fig. 50 5 showing the corresponding operative position of the parts when set for the lower ribbon field. Fig. 6 is a perspective view of the ribbon vibrating and controlling mechanism.

As appears from Figs. 1 and 2, the main frame of the machine comprises a base 1, 55 corner posts 2 and a top plate 3 which supports stationary rails 4 on which runs a carriage truck 5. A platen 6 is mounted in a platen frame 7 which is supported on said truck by links 8 so that said platen frame 60 can be shifted up and down to change case. Said platen frame comprises a cross bar 10 on which is journaled a roller 11 that is adapted to run on a shift rail 12 supported by upright arms 13 rising from a transverse 65 bar 14 which is supported by upright rods 15, each rod being pivoted at its lower end at 16 to a shift key lever 17 which is operated by a shift key 18. The platen normally stands in its lower case position as shown in 70 Fig. 1 but may be shifted upward by depressing either of the shift keys 18.

Fig. 3 shows the platen in shifted position. The rail 12, cross bar 14 and uprights 13 and 15 constitute a shiftable frame for 75 controlling the shifting movements of the platen. Printing key levers 19 are provided with keys 20 and are connected by links 21 with sub-levers 22, said sub-levers in turn being connected by links 23 with front-strike 80 type bars 24 mounted on hangers 25 secured to a stationary segmental support 26. A universal bar 27 underlies the key levers and is supported on arms 28 depending from 85 crank arms 29 which project rearward from 30 a transverse rock shaft 30 pivoted at its ends in the sides of the base. Projecting from said rock shaft near its middle is an arm 31 which is connected by a link 32 with certain of the escapement devices (not shown). 90 Ribbon spools 33 are supported one at each side of the machine below the top plate on shafts 34, and a ribbon 35 is wound on said spools and led upward therefrom through openings in the top plate, thence over stationary guides 36 and through slots formed in the head of a ribbon vibrator 37 arranged about centrally between said stationary guides. The means for turning the spools in alternation to feed the ribbon longitudinally are not herein disclosed but are preferably of the ordinary construction found in 95 the Remington machine.

As clearly appears from Figs. 2 and 6, the vibrator is off-set rearwardly below its 105 head and is provided with a depending stem-

like portion 38 which is guided in slots in a bracket 39 secured to the rear of the type bar segment 26, the construction permitting free up and down vibratory movements of 5 the vibrator 37. Secured to the stem 38 is a rearwardly projecting stud 40 through which the vibrator is connected with novel 10 vibrating devices and means for regulating the same now to be described. The stud 40 is formed with a groove which is engaged by the forked end of a laterally extending 15 horizontal lever 41 fulcrumed at 42 on a bracket 43 secured to the cross bar 14. The opposite arm of the lever 41 is connected by a vertically disposed link 44 with the 20 horizontal arm of an operating member of bell crank 45 fulcrumed at 46 to a bracket 47 secured by screws 47 to the transverse bar 14, said bracket shifting with said bar 25 when the platen shifting frame is actuated. The downwardly extending arm of the bell crank 45 is formed with oppositely disposed 30 arcuate slots 48 and 49, the slot 48 opening rearward and being nearer the axis of motion or fulcrum 46 than is the slot 49, which latter slot is closed at its rear end and open at its forward end. The slot 48 is engaged by a lateral stud or headed pin 50 fixed to the rear end of a link or actuator 51 pivotally 35 connected at its forward end 52 to an upright arm 53 secured to the rock shaft 30. Similarly the lower slot 49 is engaged by a headed pin or stud 54 extending laterally from a link or actuator 55, the forward end 40 whereof is pivotally connected at 56 with the crank arm 53. It will be observed that the connecting point 56 is nearer the axis of motion of the rock shaft 30 than is the connecting point 52.

40 In order to connect the links 51 and 54 alternatively with the bell crank 45 a hand controlled coupling device or connector is provided which in the present instance is in the form of an arm 57 pivoted at 58 to an 45 extension 45^a of the bell crank 45. The arm 57 lies close to the left-hand face of the bell crank and extends horizontally rearward from the pivot 58. Said arm is provided with a finger or engaging device 59 which 50 extends downward and is adapted to cooperate with the front of the stud or engaging device 54. The rear end of the arm 58 terminates in an upwardly extending finger or engaging device 60 which is adapted to 55 operate with the side of the stud or engaging device 50 when the downward finger 59 is in inoperative position as shown in Figs. 5 and 6. An upwardly extending link 61 connects the coupling device 57 with the 60 rear arm of a lever 62 fulcrumed at 63 on a boss or projection 64 on the bracket 47. The forward arm of the lever 62 terminates in a rounded finger 65 and said finger engaging in a cam slot formed in an extension 65 66 of a slidable bar 67, said cam slot com-

prising an inclined or cam portion proper 68 and terminating at its ends in horizontal portions or dwells 69 and 70 (Figs. 1 and 6). The slide bar 67 except for the slotted extension 66 resembles in construction the 70 slidable stop bar heretofore employed in the Remington machine. The stop bar 67 is formed with guide slots 71 to coöperate with screws 72 which screws enter the transverse bar 14 and retain the bar 67 against the rear face of said bar 14. The slide bar 67 is or may be provided with upright stop portions or fingers 73 and 74 and are adapted to coöperate with the stud 40 to limit the vibratory movements of the ribbon vibrator.

80 The slide bar 67 is provided at its left-hand portion with a vertical slot 75 through which the bar 67 is connected with manually controlled devices for moving it back and forth longitudinally. Said devices include 85 a stud 76 which projects into the slot 75 from the upper end of a crank arm 77 to which said stud is secured. The crank arm is fixed to the rear end of a horizontally disposed and forwardly extending rock shaft 90 78, said rock shaft bearing at its rear in a bracket 79 secured to the type bar segment 46. The forward end of the rock shaft bears in a plate 80 suitably secured to the left-hand front corner post. Forward of the bearing 80 the rock shaft 78 is provided with a finger button or key 81 by which the shaft may be given rotary movements to cause the stud 76 to slide the bar 67 back and forth. The construction is such that though the 95 key 81 is mounted on the frame of the machine and the bar 67 is on the shift frame, the pin and slot connection 76 and 75 permits shifting movements of the bar independently of and without obstruction from 100 the key and the parts fixedly related thereto. A finger or pointer 82 secured to the rear of the finger button 81 is adapted to coöperate with indicating marks on the front of the plate 80 to indicate the position of the 105 controlling mechanism for the ribbon vibrating devices. In one of the plurality of positions in which this controlling mechanism may be set the ribbon is adapted to vibrate to such an extent as to present only its upper field or half to the types at printing operation while when the controlling mechanism is set in another position the vibrating mechanism will give a greater extent of throw to the vibrator at printing operation 110 and so as to present the lower field or stripe of the ribbon to the types. This will be more clearly understood from the following explanation of the mode of operation of my invention.

115 My improvements are particularly adapted for use with a two-color ribbon, and accordingly I have illustrated the ribbon 35 as divided longitudinally into two fields of 120 different characteristics or colors, the upper 125 130

field *a*, for example, being black and the lower field *b* red. Let it be assumed that the parts are in the normal relationship shown in Fig. 1, 2 and 6. In these views 5 the platen is shown in lower case position and the coupling device or controller 57 is shown set in its upper position with the finger 60 in operative engagement with the stud 50, thus rendering the link or actuator 10 51 operative on the bell crank 45. The controller 57 is held up in the position described by the link 61 which in turn is controlled by the lever 62, said lever 62 having its finger 65 engaged with the dwell 69 of the cam 15 slot, thus maintaining the forward end of the lever in its lower position and the rear end thereof raised in upper position. If now one of the printing keys 20 be depressed it will operate on the universal bar 27 to 20 lower the latter, causing the rock shaft 30 to turn on its axis and swinging the arm 53 rearward or in the direction of the arrow in Fig. 6. This movement of the arm 53 will push the links 51 and 55 both longitudinally rearward and the motion of the link 25 51 will be transmitted through the stud 50 to the finger 60 and thence to the bell crank 45, swinging the downward arm of said bell crank rearward and lowering the horizontal 30 arm thereof, pulling down the link 44 and through the lever 41 raising the vibrator 48, the parts being so adjusted that the vibrator will be lifted far enough to present the lower ribbon field *b* to the types. During 35 this movement the stud 54 will play idly in the slot 49. When the vibrator has reached the printing position as above described the bell crank 45 and associate parts will be in the position illustrated in Fig. 5. It will be 40 understood that during the movement from the Fig. 1 to the Fig. 5 position the link 61 will swing about its pivotal point of connection with the lever 62 as a center but this so nearly coincides with the pivotal axis of 45 the bell crank lever 45 that the relationship of the link 61 and arm 57 with the bell crank 45 is substantially the same in the normal and operative positions. Upon releasing the printing key the ribbon vibrating mechanism will be restored to normal 50 position by gravity and the usual or other suitable restoring springs.

Assuming that it be desired to write on the upper or black field *a* of the ribbon the operator turns the button or key 81 so as to cause the stud 76 to act on the slide bar 67 and slide it inward or toward the middle of the machine until arrested by the engagement of the ends of the slots 71 with the screws 72. If then the key 81 be released the slide bar and the connected parts will be retained set in the new position by reason of the frictional engagement of the slide bar itself with the rear face of the transverse 60 bar 14. During the inward sliding move- 65

ment of the bar 67 the cam or inclined slot 68 will act on the finger 65 to raise the latter and cause it to engage with the dwell 70 which is at a greater elevation than the slot portion 69, the result being that the forward 70 arm of the lever 62 will be raised and the rear arm depressed, thereby lowering the link 60 and swinging the arm 57 downward on its pivot 58, bringing the finger 59 into operative position contiguous to the front of 75 the stud 54 and disengaging the finger 60 from the stud 50. This operation results in disconnecting one actuator from the operating member 45 and connecting the other therewith without moving the actuators 80 themselves which have a constant normal relationship. The result will be that when thereafter one of the printing keys is operated, causing the arm 53 to swing rearward, the movement of said arm will be transmitted to the bell crank 45 through the lower actuator or link 55. The relationship and adjustment of the parts is such that a less extent of movement will be transmitted to the bell crank by the lower link, and the vibrator will in consequence not be lifted or vibrated so high as previously but to a lesser extent and with the result that the upper ribbon field *a* will be presented to the types. During this movement the stud 50 90 will play idly in the slot 48. The operated position of the parts when set in this relationship is illustrated in Fig. 4. My improvements have the advantage over prior known constructions of simplicity and ease 95 and certainty of operation and are particularly adapted for use with a machine of the shifting platen variety since the relationship of the parts of the ribbon vibrating and controlling mechanism is not substantially 100 effected by the shifting of the platen. This latter advantage will be best understood from a comparison of Figs. 2 and 3 which respectively show the parts in lower and upper case positions. In shifting from 105 lower case to upper case it will be seen that the bracket or support 47 will shift upward with the shifting platen frame and platen and will carry with it the bell crank 45 and the parts supported thereon including the 110 arm 57, link 61 and lever 62. Since the slide bar 67, lever 41 and vibr. or 37 also shift with the platen the relationship of the vibrator and the train of devices for actuating and controlling the same down to and 115 including the bell crank 45 and controller 57 will be the same subsequent to the shift as before. The rock shaft 30 and arm 53 of course are not effected by the platen shift and the only change in the train of ribbon 120 devices which does take place is that the two links 51 and 55 will swing upward on their respective pivotal connections 52 and 56 from positions a little below the horizontal 125 to corresponding position slightly above the

horizontal. The action of the links on the bell crank 45 will not be substantially effected by the shift.

Various changes may be made without departing from the spirit of my invention.

What I claim as new and desire to secure by Letters Patent, is:—

1. In a typewriting machine, the combination of a ribbon vibrator, an operating member, connection between said operating member and said vibrator, a plurality of key operated actuators, and a device operative independently of said actuators and of said ribbon vibrator for connecting said 10 actuators at will with said member.

2. In a typewriting machine, the combination of a ribbon vibrator, an operating member, connections between said operating member and said vibrator, a plurality of 20 key operated actuators, and a device mounted on said member for alternatively connecting said actuators with said member.

3. In a typewriting machine, the combination of a ribbon vibrator, an operating member, connections between said operating member and said vibrator, a plurality of key operated actuators, a device supported on said member, and key controlled means 25 for setting said device independently of 30 said member to connect said actuators alternately with said member.

4. In a typewriting machine, the combination of a ribbon vibrator, an operating member, connections between said member and said vibrator, a plurality of key controlled actuators having an unvarying normal position, and means for separately connecting said actuators with said member, said vibrator remaining quiescent during 35 40 the connecting and disconnecting operations of said means.

5. In a typewriting machine, the combination of a ribbon vibrator, an operating member, connections between said member and said vibrator, a plurality of key controlled actuators having an unvarying normal position, and means for operating independently of said member and of said vibrator and also of said actuators for connecting 45 50 said actuators separately with said member.

6. In a typewriting machine, the combination of a ribbon vibrator, an operating member, connections between said member and said vibrator, a key controlled universal bar, links operative by said universal bar and having an unvarying normal relationship therewith, and means for at will rendering said links operative on said member, said means operating independently of movement of said vibrator.

7. In a typewriting machine, the combination of a ribbon vibrator, an operating lever, connections between said lever and said vibrator, a key controlled universal

bar, a pair of links operative by said universal bar, and devices operative independently of said links and of said vibrator for connecting them at will with said operating lever.

8. In a typewriting machine, the combination of a ribbon vibrator, an operating lever, connections between said lever and said vibrator, a key controlled universal bar, a pair of links operative by said universal bar, and devices for at will connecting said links with said lever, said links and said vibrator remaining quiescent during the connecting operation.

9. In a typewriting machine, the combination of a ribbon vibrator, an operating lever, connections between said lever and said vibrator, a key controlled universal bar, a pair of links operative by said universal bar, and a device supported on said operating lever for connecting said links alternatively thereto.

10. In a typewriting machine, the combination of a ribbon vibrator, an operating lever, connections between said lever and said vibrator, a key controlled universal bar, a pair of links operative by said universal bar, a coupler pivoted on said lever, and means for moving said coupler to connect said links alternatively with said lever.

11. In a typewriting machine, the combination of a ribbon vibrator, an operating lever, connections between said lever and said vibrator, printing keys, a rock shaft controlled by said printing keys, links operative from said rock shaft, and a coupler settable independently of said links and of said lever for operatively connecting said links at will with said lever.

12. In a typewriting machine, the combination of a platen, a platen shifting frame, a ribbon vibrator, an operating lever mounted on said shifting frame, connections between said lever and said vibrator, a key controlled universal bar, links operative by said universal bar, and means on said shifting frame for connecting said links at will with said operating lever.

13. In a typewriting machine, the combination of a platen, a platen shifting frame, a ribbon vibrator, an operating lever mounted on said shifting frame, connections between said lever and said vibrator, a key controlled universal bar, links operative by said universal bar, and means on said shifting frame for connecting said links at will with said operating lever, said means being controlled by a key having the same position for both shift positions of the platen.

14. In a typewriting machine, the combination of a ribbon vibrator, a lever pivotally connected thereto, a bell crank, a link connecting said bell crank and said lever, two actuating links engaging slots in said bell crank, a key controlled coupler on said bell

crank, key levers, a universal bar operative thereby, a rock shaft connected to said universal bar, and a crank arm on said rock shaft to which said actuating links are connected.

15. In a typewriting machine, the combination of a platen, a platen shifting frame, a ribbon vibrator, a lever fulcrumed on said shifting frame and pivotally connected to said vibrator, a bell crank mounted on said shifting frame and connected to said lever, two actuating links engaging slots in said bell crank, a coupler for said links mounted

on said bell crank, key levers, and a rock shaft supported on the machine frame and operative by said key levers, said actuating links being connected to and operative by said rock shaft.

Signed at borough of Manhattan, city of New York, in the county of New York, and State of New York, this 18th day of August, A. D. 1911.

JOHN H. BARR.
